US0D1004509S

(12) **United States Design Patent** (10) **Patent No.:** **US D1,004,509 S**
(45) **Date of Patent:** ** Nov. 14, 2023

(54) **VEHICLE ROOF**

(71) Applicant: **PACCAR Inc**, Bellevue, WA (US)

(72) Inventors: **Jeffrey P. Smith**, Prosper, TX (US);
Victor Garcia, Aubrey, TX (US);
Bradley D. Powell, Corinth, TX (US);
Derek S. Sancer, Corinth, TX (US)

(73) Assignee: **PACCAR Inc**, Bellevue, WA (US)

(**) Term: **15 Years**

(21) Appl. No.: **29/719,317**

(22) Filed: **Jan. 2, 2020**

Related U.S. Application Data

(63) Continuation of application No. 29/622,497, filed on Oct. 17, 2017, now Pat. No. Des. 881,097.

(51) **LOC (14) Cl.** **12-08**

(52) **U.S. Cl.** **USPC** **D12/96**

(58) **Field of Classification Search**

USPC D12/96, 13, 14, 84, 93, 95, 99, 159, 181,

(57) **CLAIM**

The ornamental design for a vehicle roof as shown and described.

DESCRIPTION

FIG. 1 is front perspective view of a vehicle roof according to our new design;

FIG. 2 is a rear perspective view thereof;

FIG. 3 is a top plan view thereof;

FIG. 4 is a front elevational view thereof;

FIG. 5 is a right-side elevational view thereof; and

FIG. 6 is a left side elevational view thereof.

The broken lines shown in the drawings depict portions of the vehicle roof that form no part of the claimed design.

1 Claim, 6 Drawing Sheets
